Application June 14, 1938, Serial No. 213,580
In France June 15, 1937

15 Claims. (Cl. 13—6)

The present invention relates to devices for the heating of liquids of the type in which heat is produced by causing electric current to flow through the mass of liquid. The invention is more especially, although not exclusively, concerned with devices of this kind for the heating of molten glass and is in part an improvement of the method and means described in the co-pending patent application of E. V. Borel, Serial No. 10 158,347, filed August 10, 1937.

In devices of this kind, the heating treatment is generally intended to produce a transformation of the liquid matter. In particular, in glass tank furnaces for the continuous production of glass, the raw materials, introduced at one end of the tank, undergo, together with the molten mass, the successive melting, fining and cooling treatments as they flow along the tank. For each of these operations, the mass is to be subjected to predetermined temperatures.

Now, in a substantially homogeneous liquid heated by electric current flowing through said liquid between electrodes, the heating effect at any point of the liquid depends upon the current density at this point, which in turn depends upon the shape of the equipotential surfaces in the liquid mass.

In glass furnaces as heretofore constructed, which are electrically heated by single phase or polyphase current at a given voltage, the current density at a given point can be varied only within narrow limits and in many cases by varying the position of the electrodes in a manner which is, for other reasons, undesirable.

For instance, when it is desired to heat a given length of the tank between a pair of electrodes, the power expended and therefore the heating effect are determined by the size of the tank and the distance between the electrodes and it can be increased or reduced by increasing or reducing the length between the electrodes. When it is desired to localise the heating action close to the electrodes by reducing their size, the power consumed is thereby reduced. As a rule, it is hardly possible to concentrate the heating in layers close to the surface of the liquid without placing the electrodes so close to each other that the heating is excessive. On the other hand, in the case of polyphase current, in order to distribute the load equally between the electrodes, it is generally necessary either to position the electrodes so that the resistances between them are equal, which is often an undesirable arrangement, or to make them of different respective sizes,

which can produce a too high localised heating at one of these electrodes.

It has also been suggested to modify the current density in the mass of glass by providing therein bodies or walls which reduce the cross sectional area through which the current flows. But these bodies are objectionable in that they cool the mass of glass and are liable to contaminate it.

The object of the present invention is to provide a device for heating a liquid bath and in particular molten glass, by controlling the current density and therefore the heating at different points of the liquid, which avoids the above mentioned drawback and in particular which does not require changing the shape of the furnace or the position of the electrodes therein.

With this, and other, objects in view, according to an essential feature of the present invention, one or more bodies of a conductivity greater than that of the liquid are immersed in the mass of the liquid in which are located two electrodes of different polarity, so as to increase the conductivity of the bath between said electrodes, or, more generally, the conductivity of the bath from one electrode to the other. These bodies may be of a conductivity so much greater than that of the liquid that their surfaces are substantially equipotential surfaces.

According to another feature of the present invention, two bodies of a conductivity higher than that of the liquid may be immersed therein in different positions relatively to each other and to the electrodes, and short-circuited.

Other features of the present invention will result from the following detailed description of some specific embodiments thereof.

Preferred embodiments of the present invention will be hereinafter described, with reference to the accompanying drawings, given merely by way of example, and in which:

Fig. 1 is a diagrammatic longitudinal vertical section of a furnace made according to the present invention;

Figs. 2, 3 and 4 are horizontal sections taken above the glass level, corresponding to respective other embodiments;

Fig. 5 is a longitudinal vertical section of a furnace according to the present invention, with electrodes for three-phase supply;

Fig. 6 is a cross-sectional view taken on the lines VI—VI of Fig. 5;

Fig. 7 is a perspective view corresponding to Figs. 5 and 6;

Figs. 8, 9, 10 and 11 are longitudinal sectional

views of a furnace according to the invention, for three-phase supply, showing different modifications of the arrangement of the electrodes and conductors.

6 In the arrangement shown by Fig. 1, the furnace 1 contains a bath of a liquid and in particular of molten glass 2, and two electrodes 3 extending transversely to the length of the tank at a small distance below the glass level. Three 10 rods 4, of a material of a conductivity higher than that of glass, are immersed in the bath between the electrodes. These rods 4 are for example of graphite. The conductivity of the glass bath is increased along the path extending from 15 one electrode to the other and passing through rods 4, while the conductivity along other paths extending through the glass from one electrode to the other remain unchanged. Consequently, the current density along the first mentioned 20 path is increased and also the heating effect along this path.

Now, in a glass furnace it is often advantageous to concentrate the heating action near the glass surface. According to the present invention, this 25 advantage is ensured by positioning rods 4 at a small depth below the glass surface, without having to modify the position of electrodes 3.

Further when rods 4 are made of a material 30 of a high conductivity as compared to that of the liquid, for instance in the case of graphite rods immersed in glass, the surface of each rod is substantially equipotential and the current density close to each of these surfaces is generally higher than at the points of the bath which 35 are at a greater distance from the surface of said rods. Consequently, the heating effect is concentrated close to the rods as indicated by the lines of current flow 5.

Furthermore, as the total conductivity between 40 electrodes 3 is increased by the provision of rods 4, the power supplied to the mass of glass for a given voltage on the electrodes is increased.

Thus, by providing conducting bodies such as 45 rods 4, immersed in the liquid mass, the heating effect can be concentrated along any desired path between the electrodes, and in particular close to said rods. Also, the total power supplied by electrodes arranged in a given position and subjected to a given voltage can be modified, according to the invention, by immersing bodies 50 such as rods 4 in the mass of liquid.

In the embodiment illustrated by Fig. 2, rods 4 are located merely in the central part of the width of the furnace, being supported by end 55 portions 6 which may be constituted by extensions of the rods covered with an insulating material.

With this arrangement, the heating effect is concentrated more in the central portion of the 60 tank than close to the walls thereof, as shown by the lines of current flow 5.

In the embodiment of Fig. 3, two rods 4 are short-circuited on the outside of the furnace by conductor 7 and consequently, these two rods 65 can be substantially at the same potential, so that the heating action can be substantially avoided between the rods 4, i. e., confined to the two regions between each of these rods 4 and the adjacent electrode 3. As far as the heating 70 action is concerned, this arrangement is thus equivalent to the existence of a single conducting body immersed in the bath and occupying the whole space between rods 4. With such an arrangement, the power consumed in the two regions 75 above mentioned is considerably higher

than would be the power consumed in the whole region extending between the electrodes in the absence in said region of rods 4.

In the embodiment of Fig. 4, these short-circuited rods 4 serve to prevent the flow of current 5 through portion 8 of the furnace, where the section is reduced, thus avoiding excessive heating in this portion 8 as would occur in the absence of said rods 4.

In the embodiment of the present invention 10 illustrated by Figs. 5, 6 and 7, the three electrodes 9, 10 and 11 are connected to the respective poles of a three-phase source of current, and they are located in a horizontal plane close to the surface of the bath in order to ensure a distribution of heat which is often desirable. Furthermore, the electrodes may be in certain cases so dimensioned as to concentrate heat close to the electrodes, while ensuring heating of the mass of glass between the electrodes. With such 20 an arrangement of the electrodes, which corresponds to a desired distribution of heat, and in the absence of bars 4, the resistance in the phase between electrodes 9 and 11 would be generally greater than in the two other phases, between electrodes 9 and 10 and between 10 and 11, so that the loads on the three phases would be unequal. But with the provision of the two bars 4, which are short-circuited by conductor 7, an alternative path of relatively low resistance 30 is formed between electrodes 9 and 11 through the short-circuited bars 4. By suitably positioning bars 4 with respect to electrodes 9 and 11 and giving them a suitable size, the combined resistances of the respective paths between the 35 three electrodes 9, 10 and 11 can be made equal and the loads on the three phases of the current are also made equal to one another.

Since the resistance between two electrodes, either directly through the bath or through bars 40 such as 4, depends upon the size of the electrodes and the bars (this resistance being the higher as the section of bars 4 is smaller) and upon the length, cross section and temperature of the mass of glass, the exact relative positioning of 45 the electrodes and bars which ensures an equal loading of the respective phases cannot be specified in a general manner and must be determined for each particular case. Furthermore, when two or more short circuited bars are employed to vary the current density, it may be 50 advantageous to place them outside of the region extending between the electrodes immersed in the bath.

In the arrangement illustrated by Figs. 5 to 7, 55 the bars 4 are so located as to provide for the heating of the glass in the vertical zones above the bars. However, when it is desired to concentrate the heating effect to a horizontal layer in the mass of glass, we may make use of one of the 60 arrangements disclosed by Figs. 8, 9, 10 and 11.

In the embodiment of Fig. 8, bars 4, which are short-circuited by conductor 7, considerably reduce the resistance between electrodes 9 and 11, while the resistance between electrodes 9 and 10 65 and between electrodes 10 and 11 is also reduced, but to a much lesser extent. Thereby, the loads on the phases may be equalized while the power expended for a given voltage is increased.

In the embodiment of Fig. 9, the resistance 70 between electrodes 9 and 11 may be reduced so as to equalize the loads on the respective phases without appreciably altering the resistance between electrodes 9 and 10 and electrodes 10 and 11.

In the embodiment of Fig. 10, bars 4 are unsymmetrically arranged, so that one bar 4 is located between electrodes 9 and 10, while the other bar 4 is located beyond electrode 11. This arrangement may be employed to compensate for the difference in the respective resistances in the paths between electrodes 9 and 10 and electrodes 10 and 11 due, for instance, to differences in their respective sizes or in the distances between them.

In the embodiment of Fig. 11, three bars 4 are employed, all three connected together by means of conductor 7. Two of these bars are positioned respectively on either side of electrode 11 so as to make the resistance between this electrode and bars 4 lower than between electrode 9 and the bars. In this way, the heating close to electrodes 9 and 11 can be made different.

In the above description of Figs. 2 to 11, it has been assumed that bars 4 are short-circuited so as to be substantially at the same potential, which is advantageous for the sake of economy and equality of power factor in the different phases. However, resistance or self-induction might be inserted in conductor 7 so as to vary the distribution of current between the electrodes. Such an arrangement permits of controlling the distribution of current through the bath by means located outside of the furnace.

Of course, while the invention has been described more specifically with reference to the treatment of a bath of molten glass, it is also applicable to the heating, due to the flow of the current through the liquid, of other liquids which are good conductors of electricity, such as salt solutions and so on.

The invention can be applied with any form of polyphase current, such as three-phase current with four electrodes, or two-phase current.

The conducting bodies, which constitute an essential feature of the present invention, may have form, position and number adapted to effect the desired variation of current density or heating in a given zone of the bath.

In a general manner, while we have, in the above description, disclosed what we deem to be practical and efficient embodiments of the present invention, it should be well understood that we do not wish to be limited thereto as there might be changes made in the arrangement, disposition and form of the parts without departing from the principle of the present invention as comprehended within the scope of the appended claims.

What we claim is:

1. An electric furnace of the type described, for the heating of a liquid, which comprises, in combination, a vessel containing said liquid, at least two electrodes adapted to supply current to said liquid and extending from one wall to the opposite wall of said vessel, and at least one body, of higher electrical conductivity than said liquid and devoid of electrical connections to any source of electrical energy except through said liquid, said body being immersed in said liquid between said electrodes and spaced away from said walls.

2. An electric furnace of the type described, which comprises, in combination, a vessel containing the liquid to be heated, at least two electrodes of different polarities adapted to supply current to said liquid extending each from one wall to the other of said vessel and both located in a plane extending below the surface of the liquid in said vessel, and at least one body, of higher electrical conductivity than said liquid, im-

mersed therein between said electrodes substantially in said plane, said body extending parallel to said electrodes and being spaced away from said walls and devoid of electrical connections to any source of electrical energy except through said liquid.

3. A glass making furnace comprising a vessel for containing a molten fluid mass, at least two electrodes of different polarities immersed in said mass for supplying electrical current thereto, and at least one body having higher electrical conductivity than said molten mass immersed in the latter between said electrodes and mounted in said vessel to extend transversely thereof so that the molten mass can flow over the top of and below the same, said body having no electrical connections to any source of electrical energy except through said mass and said electrodes.

4. A glass making furnace, comprising a vessel for containing a molten glass mass, at least two electrodes adapted to supply electrical current to said molten mass, each of said electrodes extending from one wall of said vessel to the opposite wall thereof and being wholly below the surface of said molten mass, and at least one body having higher electrical conductivity than said molten mass immersed in the latter between said electrodes in the normal path of electric current from one electrode to the other and so mounted in the vessel that said mass is free to flow over the top of and below the same, said body being devoid of electrical connections to any source of electrical energy except through said mass.

5. A glass making furnace, comprising a vessel for containing a molten glass mass, at least two electrodes of different polarities contacting said mass for supplying electric current thereto, and at least one body having higher electrical conductivity than said molten glass mass immersed in the latter between said electrodes, said body being elongated and disposed horizontally in said vessel and supported at the ends thereof so as to permit free flow of the mass completely around said body in contact with the longitudinal surfaces thereof, said body being devoid of electrical connections to any source of electrical energy except through said mass.

6. A glass making furnace, comprising a vessel for containing a molten glass mass, at least two electrodes of different polarities contacting said mass for supplying electric current thereto, and at least one elongated body having higher electrical conductivity than said molten glass immersed in the latter in spaced relation to said electrodes and in the path of electric current flowing from one of said electrodes to another of said electrodes, said body being horizontally disposed with the longitudinal axis thereof extending transversely of the furnace and being so mounted with relation to the furnace walls that said mass may flow freely around the periphery of the portion thereof within the vessel, said body being devoid of electrical connections to any source of electrical energy except through said mass.

7. A glass making furnace, comprising a vessel for containing a molten glass mass, at least two electrodes in contact with said mass and connected to different terminals of a source of electrical energy for supplying electric current to said mass for heating the latter, and at least one body having higher electrical conductivity than said mass immersed therein in the path of electric current flowing between two of said electrodes and spaced from the bottom of the ves-

- sel, said body being devoid of electrical connections to any source of electrical energy except through said mass and being supported at its ends in said vessel so that said mass is free to flow completely around the portion thereof within the vessel, the surface area of said body in contact with said mass being relatively small to provide a relatively greater electric current density in the zone immediately surrounding said body than in other parts of the mass.
8. A glass making furnace, comprising a vessel for containing a molten glass mass, at least two electrodes in contact with said mass and connected to different terminals of a source of electrical energy for supplying electric current to said mass, at least one body having higher electrical conductivity than said mass in said vessel between said electrodes, the only electrical connection between said body and a source of electrical energy being said glass mass and said electrodes, said electrodes and body being elongated and extending horizontally and parallel to one another across the width of said vessel wholly below the surface of said mass so that the latter is free to flow entirely around the same and contact the entire surfaces thereof intermediate their ends within the vessel, the surface areas of each of said electrodes and body in contact with said mass being sufficiently small to provide a large electrical current density in the zones adjacent said electrodes and body, thereby creating higher temperatures in said zones than elsewhere in the mass.
9. A glass making furnace, comprising a vessel for containing glass in a liquid state, at least two electrodes of different polarities immersed in said glass for supplying electrical current to the latter, said electrodes being spaced from each other and extending across substantially the entire width of said vessel, and at least one body having higher electrical conductivity than said glass immersed therein between said electrodes and mounted so that the glass may flow over the top of and below the same, said body having no electrical connection with any source of electrical energy except through said materials and electrodes, the surface areas of each of said electrodes and said body being such that the electric current density in said glass mass is greatest in the zones immediately surrounding said electrodes and body.
10. A glass making furnace, comprising a vessel for containing a molten glass mass, at least two electrodes of different polarities contacting said mass for supplying electrical current thereto, at least two elongated, horizontally disposed bodies of higher electrical conductivity than said mass, said bodies extending across the width of said vessel and being immersed within said mass in spaced relation to the electrodes and the bottom of the vessel and supported at their ends so as to permit free flow of the mass completely around said bodies in contact with longitudinal surfaces thereof, and an electrical conductor interconnecting said bodies, said bodies being in the path of electric current between said electrodes and devoid of electrical connections to any source of electrical energy except through said
- mass, said conductor being devoid of electrical connections to any source of electrical energy except through said bodies.
11. A glass making furnace comprising a vessel for containing a molten glass mass, at least two electrodes of different polarities contacting said mass for supplying electrical current thereto, at least two horizontally disposed bodies of higher electrical conductivity than said mass immersed in the latter and supported at their ends to extend across the normal path of electric current between said electrodes, and an electrical conductor interconnecting said bodies, said bodies being devoid of electrical connections to any source of electrical energy except through said mass, said conductor being devoid of electrical connection to any source of electrical energy except through said bodies.
12. An electric furnace of the type described for the heating of a liquid, which comprises, in combination, a vessel containing said liquid, at least three electrodes adapted to supply polyphase current into said liquid, arranged so that the respective resistances of the liquid paths in the different phases are different, two bodies each of higher electrical conductivity than said liquid immersed therein close to the two electrodes between which the resistance of the liquid path for the current is higher, and a conductor interconnecting said two bodies.
13. An electric furnace of the type described for the heating of a liquid, which comprises, in combination, a vessel containing said liquid, at least three electrodes adapted to supply three-phase current into said liquid and located substantially in a horizontal plane, two bodies, each of higher electrical conductivity than said liquid, immersed therein close to the two extreme electrodes respectively, and a conductor interconnecting said two bodies.
14. An electric furnace of the type described for the heating of a liquid, which comprises, in combination, a vessel containing said liquid, three electrodes adapted to supply three-phase current into said liquid and located substantially in a horizontal plane, two bodies, each of higher electrical conductivity than said liquid, immersed therein close to the two extreme electrodes respectively and substantially in said horizontal plane, and a conductor interconnecting said two bodies.
15. An electric furnace of the type described for the heating of a liquid, which comprises, in combination, a vessel containing said liquid, three electrodes adapted to supply three-phase current into said liquid and located substantially in a horizontal plane, two bodies, each of higher electrical conductivity than said liquid, immersed therein on either side of one of the extreme electrodes and substantially in said horizontal plane, a third body, also of higher electrical conductivity than said liquid, immersed therein close to the other extreme electrode and substantially in said horizontal plane, and a conductor interconnecting said three bodies.

EDOUARD VIRGILE BOREL,
YVAN PEYCHES.
